(57) **CLAIM**

The ornamental design for the dive regulator, as shown and described.

DESCRIPTION

FIG. 1 is a first perspective view of the dive regulator; FIG. 2 is a second perspective view of the dive regulator; FIG. 3 is a third perspective view of the dive regulator; FIG. 4 is a rear view of the dive regulator; FIG. 5 is a front view of the dive regulator; FIG. 6 is side view of the dive regulator; FIG. 7 is a side view thereof showing the side opposite that shown in FIG. 6; FIG. 8 is a top view of the dive regulator; and, FIG. 9 is a bottom view of the dive regulator. The broken lines in the drawings are included for the purpose of illustrating portions of the dive regulator and form no part of the claimed design.
